CLAIM

The ornamental design for a shoe outsole, as shown and described.

DESCRIPTION

FIG. 1 is a front perspective view of a shoe outsole showing my new design;

FIG. 2 is a rear perspective view thereof;

FIG. 3 is a plan view thereof;

FIG. 4 is a front perspective view of an alternate embodiment of the design shown in FIGS. 1-3;

FIG. 5 is a rear perspective view of FIG. 4; and,

FIG. 6 is a plan view of FIG. 4.

The broken lines immediately adjacent to the shaded area represent an unclaimed boundary of the design. The broken lines showing the channels in FIGS. 1-3 and the remainder of the shoe illustrate the portions of the design that form no part of the claim. Neither the broken lines nor the areas within them form any part of the claim.
